 Bronxville, N. Y., assignors to Servo Control
 Company, Inc., a corporation of New York

Application July 30, 1949, Serial No. 107,688

21 Claims. (Cl. 187—29)

1

This invention relates to an improved and simplified automatic elevator control system in which many of the complex relays heretofore employed are eliminated by a system employing balanced potentials or signals based upon a comparison of voltages representing each floor level with a voltage variable with the car level.

A further improvement is the use or adaptation of a hydraulic valve and a self-locking hydraulic motor to motivate the elevator car. In this system, the control is effected by controlling the stroke of a constantly driven pump, so that a variable supply is delivered to a reversible motor connected to the elevator cables. Such a system is self-locking, light, and of maximum reliability.

The electric controls operate on the principle of having a signal generating means which produces a definite signal or voltage representing each floor level and which is matched against a variable signal or voltage producing means turned or positioned by the elevator car, so that the elevator car is always moved to a position at which these two signals are matched before coming to rest, and such position is at the floor level signaled by one of the call buttons. Thus, there is produced an elevator system which may be fully automatic or semi-automatic and which is self-leveelling with a minimum number of interlocking relays and parts. This system also automatically provides for uniform rapid acceleration of the car since the initial signal delivered is proportional to the difference between the floor levels at which the car is positioned at the time and to which it is signaled, subject, of course, to a safe maximum speed, which is controlled by an additional signal generator producing a counter-voltage proportional to elevator speed. For smooth decelerating, an additional signal generator responsive to the rate deceleration may be provided to limit this rate within safe and comfortable limits.

Other features will be apparent from the following description and claims.

Referring to the drawings in which a preferred embodiment of the invention is shown,

Fig. 1 is a simplified wiring diagram of the call button and step switch control circuits;

Fig. 2 shows an additional portion of the wiring diagram showing a third unit of the step switch and the balanced potentiometer system which produces a net signal which is fed to the amplifier and servomotor;

Fig. 3 is a wiring diagram of the amplifier and counter-signal producing means to which the net signal is fed, and a diagrammatic representation

2

of the servomotor system which actuates the elevator car; and

Fig. 4 is a wiring diagram showing the apparatus of Figs. 2 and 3 modified so that an alternating current power source is employed to energize the apparatus which produces the control signals.

In the diagram of Fig. 1 there is shown our system applied to a five-story building. One set of call buttons is shown, but it will be understood that the same system may be applied to any number of floors desired and a duplicate set of up and down call buttons will be provided on the cars as well as at each floor.

Referring now to Fig. 1, call buttons 10, 11, 12, 13, 14, 15, 16 and 17 are located on the various floors and serve to produce the fifth floor down, fourth floor up, third floor up, second floor up, fourth floor down, third floor down, second floor down and the first floor up signals respectively. Identical relays 20, 21, 22, 23, 24, 25, 26 and 27 are respectively operated by means of call buttons 10—17 and battery 28. Each of these relays is of the hold-in type so that after it is operated it will remain operated until released by a control circuit which is described hereinafter. Indicating lights 29 are preferably provided in parallel with the windings of relays 20—27 to indicate when these relays are operated.

Three step switch sections 31, 32 and 33 are mounted on a common shaft 35 and the shaft 35 is actuated by means of pawl and ratchet mechanism 37. When solenoid 39 is energized it pulls armature 41 and pawl 42 down, thereby opening contacts 44 and de-energizing solenoid 39 so that spring 46 restores armature 41 and pawl 42 and causes ratchet wheel 48 to rotate one notch. This rotates shaft 35 and causes the rotors of switches 31, 32 and 33 to advance one position.

Switch 49 is momentarily closed each time the elevator door is closed. This switch 49 may be located in the elevator cab or a switch may be provided for each floor. For the latter arrangement, the switches for the various floors are connected in parallel.

The windings of relays 50, 51, 52, 53, 54, 55, 56 and 57 are energized by switch 49 and battery 58 through step switch 32, and these relays serve to release relays 20—27 respectively.

The winding of relay 59 is connected in series with each of the windings of relays 50—57 so that the winding of relay 59 is also energized by means of switch 49.

Fig. 2 shows a bridge circuit which is employed

to produce the signals which control the movement of the elevator cab.

Potentiometers 61 and 62 are connected across battery 63. Potentiometer 61 has five taps and each tap provides a reference voltage which designates one floor.

For example, the fifth floor is represented by tap 64 which is 85 volts above ground, the fourth floor by tap 65 which is 65 volts above ground, the third floor by tap 66 which is 45 volts above ground, the second floor by tap 67 which is 25 volts above ground, and the first floor by tap 68 which is three volts above ground potential. After the taps 64-68 are adjusted to supply the various voltages required, no further adjustment is required.

The rotor of potentiometer 62 is rotated by shaft 70 which in turn is rotated by means of a mechanical linkage connected to the elevator car (Fig. 3). When the elevator car is at the first floor, the rotor of potentiometer 62 is at the same potential as tap 68 on potentiometer 61. When the elevator car is at the second floor the rotor of potentiometer 61 is at the same potential as tap 67 on potentiometer 61, and so on to the fifth floor, where the rotor of potentiometer 61 is at the same potential as tap 64.

The rotor of potentiometer 62 is connected to one side of resistor 72 and the taps of potentiometer 61 are selectively connected by means of switch 33 to the other side of resistor 72.

The voltage across resistor 72 is applied over conductors 76 and 77 to a servo amplifier 74 (Fig. 3) which serves to actuate the elevator car moving mechanism. As will be explained hereinafter, amplifier 74 and the car moving mechanism constitute a servo apparatus which actuates the armature of potentiometer 62 so that potentiometer 62 is caused to produce a voltage equal to the voltage on the tap of potentiometer 61 as selected by step switch section 33.

Referring now to Fig. 3, the control signal across leads 76 and 77 is applied to the servo amplifier input resistor 79 through an R-C. network comprising resistor 80 and condenser 82, 45

40 The direct current signal across resistor 79 is converted to an alternating current signal by means of vibrator 85 and transformer 87 in a conventional manner. The winding of vibrator 85 is energized by an alternating current from source 89 which may be a 60 cycle power line.

The signal induced in the secondary of transformer 87 is amplified by power amplifier 74 and applied to field winding 91 of a two-phase A. C. motor 92 through transformer 94. The other field winding 96 of motor 92 is separately excited from source 98 which is of the same frequency as source 89 and may be a 60 cycle power line.

60 While motor 92 might be used directly to raise and lower the elevator car or to control an electric motor driven system, I prefer to interpose a hydraulic motor system in order to achieve maximum safety.

Accordingly, motor 92 is coupled through gears 100 to gear 102 which actuates gear 103 and arm 104 about pivot 105. Stops 106 are provided to limit the movement of gear 103 and arm 104.

65 The force applied to hydraulic booster 106 is increased by booster 106 and applied to a variable delivery hydraulic valve and pump 108. When arm 109 of the hydraulic valve and pump 108 is moved off center in one direction, the hydraulic valve and pump 108 permits the hydraulic fluid to flow clockwise through the hy-

draulic valve and pump 108, pipes 111 and hydraulic motor 113; and when arm 109 is moved off center in the other direction, the hydraulic valve and pump 108 permits the hydraulic fluid to flow counterclockwise through the hydraulic system. When arm 109 is at its central or neutral position, the hydraulic fluid is not permitted to circulate and the hydraulic motor 113 is locked.

70 Constant speed motor 115 serves to actuate the hydraulic pump of unit 108, and motor 115 is preferably energized with three-phase alternating current.

75 Hydraulic motor 113 and pump 108 may be a variable delivery reversible, self-locking type such as shown in the patent to T. B. Doe, 2,177,098, dated October 24, 1939.

The rotary output of hydraulic motor 113 is applied to reduction gearing 117 which actuates pulley 119 which in turn moves the elevator car 120 up and down by means of cables 122.

80 The elevator car 120 is connected to control potentiometer 62 by means of cable 124, pulley 126, gears 128 and shaft 70. A weight 129 is provided on one end of cable 124 to maintain a constant tension on the cable.

85 Tachometer 130 is actuated by the shaft of motor 92 and serves to produce a D. C. voltage which is applied through potentiometer 131, resistor 132 and condenser 133 to resistor 83 in the same polarity as the D. C. signal applied to the amplifier input resistor 79 through resistor 83 by means of leads 76 and 77.

90 When the elevator car 120 is moved from one floor to another, motor 92 first rotates until gear 103 strikes one of the stops 106 and later, due to the action of potentiometers 62 and 81, as explained hereinafter, motor 92 is caused to rotate in the opposite direction until gear 103 is centered between stops 106. Thus, each time motor 92 rotates, a D. C. signal is produced by tachometer 130 which aids the main control signal produced across leads 76 and 77. In this manner the rate of acceleration and the rate of deceleration of elevator car 120 is controlled, the amount of control being determined by the voltage produced by tachometer 130, the setting of potentiometer 131 and the time constant of resistor 132 and condenser 133, so as to limit the rate within safe and comfortable limits.

95 The rotor of potentiometer 81 is actuated by the shaft of motor 92 through gears 100, gears 135 and shaft 137. When a signal is applied to amplifier 74 over leads 76 and 77, motor 92 is caused to rotate first in one direction and this causes the rotor of potentiometer 81 to be offset from its center position to produce a voltage which is applied to the amplifier input resistor 79 in opposite polarity to the main control signal across leads 76 and 77. When motor 92 is caused to rotate in the other direction and is restored to its initial position, the rotor of potentiometer 81 is slowly restored to the midpoint of the resistance element.

100 Thus, two auxiliary signals are algebraically added to the main control signal supplied by leads 76 and 77. The first of these auxiliary signals is produced by tachometer 130 and the magnitude of this auxiliary signal is proportional to the acceleration or deceleration of the elevator car 120. The second auxiliary signal is produced by potentiometer 81 and the magnitude of this signal is proportional to the car speed.

105 The system operates as follows: Assuming the elevator car 120 to be at rest on the first floor,

if the fourth floor up call button 11 is pressed (for example), the winding of relay 21 will be energized by current flowing from battery 28 through button 11, the winding of relay 21, the normally closed contacts of relay 51, and the winding of relay 59 to ground, thus operating the armatures of relays 21 and 59. The connection between the armature and front contact of relay 21 serves to maintain relays 21 and 59 in an operated condition after button 11 is released. The back contact of relay 21, which is connected to contact 139 on switch 31, is now de-energized.

Assuming that the second and third floors have no up calls, contacts 141 and 143 will be energized by battery 28 and the released armatures of relays 22 and 23 respectively. The armature of relay 27 is operated since the car is at the first floor and, hence, contacts 145 and 146 of switch 31 are de-energized. When the elevator car doors are closed by the operator, switch 49 will close momentarily and energize the winding of relay 57 through contacts 148 and 149 of switch 32. Thus, the armature of relay 57 operates momentarily and de-energizes the winding of relay 27 so that the armature of relay 27 is released.

Solenoid 39 is now energized by battery 28 through the armature and back contact of relay 27, contacts 145 and 146 of switch 31, contacts 44, and the contacts of relay 59. The stepping mechanism will now step shaft 35 around to move the rotors of switches 31, 32 and 33 from contact to contact until a de-energized contact on switch 31 is reached. For the example under consideration, contact 139 is the first de-energized contact on switch 31. Since stepping switches are available which operate as fast as one step per one-tenth second, the rotor of step switch 31 can reach contact 139 before the car door is completely closed.

When the rotor of switch 31 reaches contact 139 the stepping mechanism is stopped since the back contact of relay 21 is not in contact with the operated armature of relay 21 and the circuit between solenoid 39 and battery 28 is open at that point.

Thus, the armatures of switches 31, 32 and 33 stop on contacts 139, 150 and 152 respectively.

The rotor of switch 33 now connects tap 65 on potentiometer 61 to lead 77. Since tap 65 is at a potential of 65 volts above ground and since the elevator car 120 is at the first floor so that the rotor of potentiometer 62 is at a potential of 3 volts above ground, a control signal of approximately 62 volts is applied across resistor 72 so that lead 77 is of positive polarity with respect to lead 76.

This control signal is applied to vibrator 85 and transformer 87 through delay network 80, 82, potentiometer 81 and resistor 83. While the elevator car 120 is still at rest at the first floor, the rotor of potentiometer 81 is at the midpoint of the resistance element of the potentiometer, no voltage is produced by tachometer 130, and the main control signal across leads 76 and 77 is not affected by the auxiliary signal circuits.

The main control signal is converted to an A. C. signal by vibrator 85 and transformer 87, and the A. C. signal is amplified by power amplifier 74 and applied to field winding 91 of motor 92 to cause the shaft of motor 92 to rotate in a counter-clockwise direction until gear 103 strikes stop 106 at which time the shaft of motor 92 stops rotating and remains stationary until it is restored to its initial position as explained hereinafter.

This counter-clockwise rotation of motor 92 causes control arms 104 and 109 to move to the left, thereby activating hydraulic motor 113 and causing the elevator car 120 to be raised.

5 The counter-clockwise rotation of motor 92 also causes the rotor of potentiometer 81 to rotate in a clockwise direction to a position near the upper end of the resistance element of potentiometer 81. In this manner a counter-signal 10 is introduced in series with lead 76 which opposes the main control signal conveyed by leads 76 and 77. For the embodiment of the invention disclosed herein, the maximum opposing voltage may be 12 volts, for example, so that the 15 main control signal is thereby reduced to 50 volts. The rotation of motor 92 also causes tachometer 130 to produce a D. C. voltage across resistor 83 in series with lead 77, which increases the control signal conveyed by leads 76 and 77 by a small 20 amount. The primary purpose of tachometer 130 is to control the rate of deceleration as discussed hereinafter. The rate of acceleration is preferably controlled by the R.-C. delay network 80, 82 across lines 76 and 77 which retards the rate of 25 increase of the control signal.

Thus, the control signal applied to amplifier 74 is initially retarded by the delay network 80, 82 and reduced by the auxiliary signal produced by potentiometer 81 and increased slightly by the 30 auxiliary signal produced by tachometer 130 so that the initial A. C. signal produced by amplifier 74 and consequently the speed of motor 92 and the acceleration of elevator car 120 are determined by the algebraic sum of the three signals. 35 When gear 103 strikes stop 106, the auxiliary signal produced by tachometer 130 begins to decrease exponentially at a rate dependent upon the time-constant of resistor 132 and condenser 133. The decrease of this auxiliary signal is 40 preferably fairly rapid.

As the elevator car 120 rises, the rotor of potentiometer 62 is rotated by means of cable 124, pulley 126, gears 128 and shaft 70 so that the voltage applied to lead 76 approaches the voltage 45 applied to lead 77. When the voltage between leads 76 and 77 is reduced to 12 volts by the rise of elevator car 120, the net control signal applied to amplifier 74 across resistor 79 will be zero since potentiometer 81 produces a counter-signal of 12 50 volts and since the auxiliary signal produced by tachometer 130 will have decayed to zero by this time. The elevator car 120 will still be rising at its maximum rate of speed at this time. However, at the next instant, the signal applied to 55 amplifier 74 across resistor 79 will reverse in polarity because the counter-signal from potentiometer 81 will exceed the signal across leads 76 and 77. An A. C. signal which differs in phase from the initial signal by 180° is now produced 60 by amplifier 74 and applied to field winding 91 of motor 92 so that motor 92 rotates in a clockwise direction and slowly closes valve 108 so as to stop motor 113 and the elevator car 120.

The speed of elevator car 120 will decrease 65 slowly as the rotor of potentiometer 81 is restored to its central position. When the rotor of potentiometer 81 is completely restored to its central position, the elevator car 120 will stop at the fourth floor, since for this condition no signal is applied to amplifier 74 and no hydraulic fluid 70 will flow through valve 108 and motor 113.

During the deceleration period tachometer 130 will generate a signal which opposes the deceleration. The amount of deceleration is determined 75 by the time-constant of resistor 132 and con-

denser 133 and by the setting of potentiometer 131. The setting of potentiometer 131 is determined empirically to produce a desired rate of deceleration of the elevator car 120, and ordinarily no further adjustment is required. Stated differently the R.-C. network 132, 133 controls the rate of change of acceleration which is the factor that causes jerks.

If the load in the elevator car 120 is changed by a large amount so that the car is raised or lowered a small distance, the rotor of potentiometer 62 will rotate a corresponding amount, and a signal will be applied to amplifier 14 which will cause motor 92 to drive off center and then back to center, thereby re-leveling the elevator car.

The operation of the hydraulic motor 113 is controlled by the displacement of relatively incompressible hydraulic fluid. When hydraulic valve 108 is in its central or neutral position, the hydraulic fluid can not flow through lines 111 and the hydraulic motor 113 is locked. Thus no power is required to hold the elevator car 120 at rest.

After the elevator car door is opened and closed by the operator, switch 49 serves to momentarily energize the winding of relay 51 through the circuit from battery 58, through switch 49, the rotor of switch 32, contact 150, the winding of relay 51, and the winding of relay 59 to ground. When the armature of relay 51 operates, the circuit which energizes the winding of relay 21 is opened and the armature of relay 21 is restored to the back contact of relay 21. Since the rotor of switch 31 is at contact 139, solenoid 39 is connected to battery 28 through the back contact and released armature of relay 21, contact 139, the rotor of switch 31, armature 41, and contacts 44. If one or more of the other call buttons have been pressed, relay 59 will be operated and the stepping mechanism 37 will step until the armature of switch 31 encounters a contact which is de-energized.

If the fifth floor down call button 10 has been pressed the apparatus will function in a manner analogous to that described above to raise the elevator car 120.

If one of the lower call buttons has been pressed, the bridge circuit formed by potentiometers 61 and 62 and switch 33 will produce a control signal which causes lead 76 to be of positive polarity with respect to lead 77. This control signal will cause motor 92 to rotate in a clockwise direction, thereby causing the hydraulic system to lower the elevator car 120.

Preferably a mechanical brake should be provided in order to hold the elevator car 120 at rest in case of electric power failure or hydraulic failure. Such a brake may be one of the types already known in the elevator art and it is not disclosed herein since it is not part of my invention.

Fig. 4 shows the apparatus of Figs. 2 and 3 modified so that an alternating current power source 98 is employed to energize the apparatus which produces the control signals.

A pair of step switch sections 160 and 162 are actuated by the shaft 35 which, as explained above with reference to Fig. 1, is actuated by means of the call buttons located on the various floors. The rotors of the switches 160 and 162 serve to selectively connect the stator windings of two of the Selsyns 164-173 across an alternating current source of potential 98 which may be a 60-cycle power line.

The rotors of the two groups of Selsyns, 164-168 and 169-173, are respectively positioned to produce signals having magnitudes which increase by increments and represent the floor levels 1 to 5, and then the rotors are locked in these positions and no further adjustment is required.

The two Selsyns 175 and 176 serve to produce alternating current signals having amplitudes proportional to the distance which the elevator car is to be moved.

The rotor windings of Selsyn 175 are connected across the locked rotor windings of Selsyns 164-168 and the rotor windings of Selsyn 176 are connected across the locked rotor windings of Selsyns 169-173.

The rotor of Selsyn 175 is turned through 175 degrees as the elevator car moves from the first to the fifth floor, the rotor being actuated by means of the shaft 70 which is connected to the elevator car by the mechanical linkage described above with reference to Fig. 3. The rotor of the Selsyn 176 is connected to the shaft 70 by gears 178 which cause the rotor of Selsyn 176 to make 15 revolutions for each 175 degree rotation of the Selsyn 175.

Thus, Selsyn 175 serves to produce a coarse control signal having an amplitude proportional to the distance the elevator car is to be moved as determined by the position of the rotor of Selsyn 175 and by the signal produced by Selsyns 164 to 168. This coarse control signal is employed to control the movement of the elevator car until the car is almost at the floor level to which it has been called. Then the fine control signal produced across the stator winding of Selsyn 176 is employed to control the movement of the elevator car until the car stops at the floor level to which it has been called. The amplitude of the fine control signal is determined by the position of the rotor of Selsyn 176 and by the signal produced by Selsyns 169 to 173.

The coarse control signal produced across the stator winding of Selsyn 175 is applied to a diode rectifier tube 180 through an R.-C. network 182, 184, and the direct current voltage developed across the R.-C. network 182, 184 is applied between the grid and cathode of an amplifier tube 186. Cathode bias for tube 186 is obtained by means of resistors 188 and 190 connected across battery 192. Thus, when the signal developed across the R.-C. network 182, 184 exceeds the cathode bias developed across resistor 188, the amplifier tube 186 draws current from battery 192 through the winding of relay 194, and the armature of relay 194 operates to connect the signal produced by the stator of Selsyn 175 across the primary winding of the amplifier input transformer 87. This signal is amplified by amplifier 14 which serves to energize the winding 91 of motor 92. The winding 96 of two-phase motor 92 is energized from the source 98 through a condenser 195 which serves to produce the necessary phase shift between the respective signals applied to the windings 91 and 96.

The rotation of the shaft of motor 92 serves to actuate the hydraulic system which in turn serves to move the elevator car as explained above with reference to Fig. 3.

As the elevator car approaches the floor to which it has been called, the magnitude of the voltage across resistor 182 decreases, and when the cathode bias across resistor 188 exceeds the voltage across resistor 182, tube 186 ceases to

draw current and the winding of relay 194 is de-energized. If further control over the operation of relay 194 is desired, a condenser 200 may be provided across the relay winding.

When the armature of relay 194 releases, the coarse control signal is disconnected from the amplifier 74 and the fine control signal produced across the stator of Selsyn 176 is applied to the amplifier 74 through a potentiometer 202. The circuit constants are proportioned so that the coarse and fine control signals are of approximately the same amplitude at the instant when the armature of relay 194 releases.

The elevator car continues to move with decreasing speed towards the floor to which it has been called until no signal is produced across the stator of Selsyn 176 at which instant the elevator car stops at the level of the floor to which it has been called.

The potentiometer 193 (which corresponds to the potentiometer 81 of Fig. 3) is connected to the source 98 through a transformer 198 and serves to produce a signal between its rotor and grounded center tap which is 180° out of phase with the main control signals produced by Selsyns 175 and 176.

The amplitude of the signal produced by the potentiometer 196 is proportional to the speed of the elevator car, and this signal is employed to partially counteract the main control signal applied to amplifier 74 as before.

The rotor of potentiometer 196 is initially offset almost to one end of its resistance element to produce a counter-signal proportional to the speed of the elevator car and then the rotor is slowly restored to the center of the resistance element as the car decelerates and stops at the desired floor level.

In this embodiment of the invention the rates of acceleration and deceleration of the elevator car are controlled by means of an inertia wheel 204 and an electromagnetic damper comprising a copper disc 206 and a magnet 208 which serve to control the acceleration and deceleration of the shaft of motor 92.

It will be apparent that various modifications can be made in the apparatus disclosed herein. For example, electric motive means may be employed instead of the hydraulic motor system, and the resistance element of potentiometer 81 or potentiometer 196 may be made non-linear. If extremely high speed elevator operation is desired, the counter-voltage introduced by the displacement of the rotor of potentiometer 81 or potentiometer 196 may be caused to vary as the square root of its displacement.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. An elevator control system comprising a motor for raising and lowering the elevator car, energizing means for said motor, means for varying the output of said energizing means, said last named means having a movable control arm, a servo system for controlling the position of said arm, a signal generator connected to the control circuit of said servo system for producing a variable signal having a magnitude proportional to the distance the elevator car is to be moved, and 75

means for limiting the rates of acceleration and deceleration of the car.

2. An elevator control system comprising a signal source adapted to produce signals which increase by an increment for each floor level, a variable signal source adapted to produce a second signal variable with the height of the elevator car, means for selectively comparing said first signals with said variable signal and producing control signals proportional to the vector sum of said first and second signals, and means responsive to said control signals for actuating the elevator car.

3. The apparatus of claim 2 further including means responsive to the speed of the elevator cab for reducing said control voltage an amount proportional to said speed.

4. An elevator control system comprising a signal source adapted to produce a plurality of signals, each signal representing a floor level and the signals increasing in strength or amplitude by an increment for each floor, a variable signal source controlled by the height of the elevator cab for producing an auxiliary signal, call means located on each floor, a step switch actuated by said call means for selectively connecting said first signals in series with said auxiliary signal in opposite polarity to produce control signals, and servo means responsive to said control signals for actuating the elevator car.

5. In an elevator control system, a reversible motor for raising and lowering the elevator car, variable energizing means for said motor, a servo system connected to said energizing means for controlling the output thereof, a source of potential, a first resistance connected across said source of potential and having taps representing the various floor levels which produce signals which increase in magnitude by an increment for each floor level, a second resistance connected across said source of potential, said second resistance having an adjustable tap, means for moving said tap along said resistance in one direction as said motor rotates in one direction and in the other direction as said motor rotates in the other direction, and means connecting said slider and for selectively connecting said taps across an impedance in said servo system to control said servo system and thereby control the rotation of said motor.

6. In an elevator system having signalling means located at the various floors and a motor for raising and lowering the elevator car and a variable energizing circuit for said motor having an input circuit responsive to a control signal, apparatus for producing a control signal comprising a source of potential, a first impedance connected across said source of potential, a movable slider on said first impedance connected to one terminal of said input circuit, means for moving said slider in one direction along said first impedance as the elevator car is moved in one direction and for moving the slider in the other direction along the impedance as the elevator car is moved in the other direction, a second impedance connected across said source of potential, said second impedance having a plurality of taps thereon, and means responsive to said signalling means for selectively connecting predetermined ones of said taps to the other terminal of said input circuit.

7. In an elevator control system, means for producing a first signal having a magnitude proportional to a predetermined floor level, means for producing a second signal having a magni-

tude proportional to the height of the elevator car, means for producing a control signal proportional to the difference in magnitude between said first and second signals, means for producing an auxiliary signal having a magnitude proportional to the speed of the elevator car and a polarity determined by the direction which the elevator car is moved, a motor for moving the elevator car up and down, variable energizing means for said motor, said energizing means having an input circuit and being adapted to cause said motor to rotate in one direction in response to an input signal of one polarity and in the opposite direction in response to an input signal of the other polarity, and means serially connecting said control and auxiliary signal producing means in opposite polarity across said input circuit.

8. In combination, a reversible motor for raising and lowering an elevator car, variable energizing means for said motor, said energizing means being adapted to cause said motor to rotate in one direction in response to a signal of one polarity and in the opposite direction in response to a signal of the opposite polarity, a bridge circuit for producing a variable control signal having a variable amplitude proportional to the distance and a polarity determined by the direction said elevator car is to be moved, interconnecting means between the output of said bridge circuit and the input of said energizing means, said interconnecting means including an impedance, and means for producing an auxiliary signal across said impedance of opposite polarity to the said control signal, said auxiliary signal having a magnitude proportional to the speed of said motor.

9. In combination, means for raising and lowering an elevator car including a reversible, self-locking hydraulic motor, a circulating system for circulating hydraulic fluid through said motor, said system including a valve adapted to control the quantity and direction of circulation of said hydraulic fluid, an electric signal source for producing a control signal having a variable amplitude proportional to the distance and a polarity determined by the direction which said elevator car is to be moved, and means responsive to the control signal produced at the output of said signal source for controlling the position of said valve.

10. In combination, means for raising and lowering an elevator car including a reversible, self-locking hydraulic motor, a closed circulating system for circulating hydraulic fluid through said motor, said system including a valve adapted to control the quantity and direction of circulation of said hydraulic fluid, a servo system for moving said valve, a source of potential, a first resistance connected across said source of potential and having taps representing the various floor levels which produce signals which increase in magnitude by an increment for each floor level, a second resistance connected across said source of potential and having a slider, means responsive to the movement of said elevator car for moving said slider along said resistance in one direction as the elevator car is moved upward and in the other direction as the elevator car is moved downward, means connecting said slider and for selectively connecting said taps across an impedance in said servo system to control said servo system and thereby control the position of said valve.

11. In combination, means for raising and lowering an object including a reversible, self-lock-

ing hydraulic motor, means for circulating hydraulic fluid through said motor, an adjustable control for said circulating means having a neutral position for preventing the circulation of fluid through said motor, said adjustable control being adapted to cause the hydraulic fluid to circulate in one direction through said motor when displaced in a first direction and adapted to cause the hydraulic fluid to circulate in the opposite direction through said motor when displaced in a second direction, a bridge circuit for producing a control signal having a variable amplitude proportional to the distance which said object is to be moved, said signal being of one polarity when the object is to be moved up and of the opposite polarity when the object is to be moved down, and servo means responsive to said control signal for actuating said adjustable control.

20 12. The apparatus of claim 11 further including means responsive to the displacement of said adjustable control for reducing the amplitude of said control signal an amount proportional to the displacement of said adjustable control.

25 13. The apparatus of claim 11 further including means responsive to said servo means for increasing said control signal an amount proportional to the acceleration and the deceleration of said hydraulic motor.

30 14. In an elevator control system, means for producing a D. C. signal having a variable magnitude proportional to the distance and a polarity determined by the direction the elevator car is to be moved, means for converting said D. C. signal to an A. C. signal having a predetermined frequency, the phase and magnitude of said A. C. signal being determined respectively by the polarity and magnitude of said D. C. signal, an A. C. amplifier actuated thereby, and means for moving the elevator car from the output of said amplifier.

35 15. The apparatus of claim 14, wherein said moving means includes a two-phase A. C. motor having one field winding connected to said A. C. signal and the other field winding connected to a second A. C. signal having a fixed phase and a frequency equal to the frequency of said A. C. signal.

40 16. In an elevator control system having a motor for raising and lowering the elevator car and an energizing circuit for said motor controlled by a control signal produced by the signalling means for the elevator car, a signal generator for producing an auxiliary signal proportional to the acceleration and deceleration of said motor, and means interconnecting said signal generator and said energizing circuit for increasing said control signal by an amount proportional to the magnitude of said auxiliary signal.

45 17. In an elevator control, call buttons for up and down operation for any floor to any other floor, a step switch set into operation by the pressing of any button, means for stopping said switch upon its reaching a position corresponding to the floor button pressed including means producing a distinctive voltage for that floor, a variable opposing voltage producing means turned by the elevator which matches said other voltage only when the elevator is at that floor, and a reversible elevator motor controlled by net voltage for raising and lowering the car.

50 18. In an elevator system having means for signaling the elevator cab, means responsive to said signaling means and to the location of the elevator cab for producing a first variable voltage

having a magnitude which varies in accordance with the distance which the elevator cab is to be moved, means for producing a second variable voltage having a magnitude which varies in accordance with the speed of the elevator cab, a motor for raising and lowering the elevator cab, and means responsive to the difference between said first and second voltages for controlling said motor.

19. In an elevator system having means for signaling the elevator cab, a signal source responsive to said signaling means for selectively producing A. C. signals having amplitudes which vary in accordance with the floor level to which the elevator cab is signaled, a Selsyn having its rotor connected by a mechanical linkage to the elevator cab and turned by the movement of the cab, one winding of said Selsyn being connected to said signal source, and motive means responsive to the signal produced across the other winding of said Selsyn for raising and lowering the elevator cab.

20. In an elevator system having means for signaling the elevator cab, a signal source responsive to said signaling means for selectively producing A. C. control signals having amplitudes which vary in accordance with the floor level to which the elevator cab is signaled, a Selsyn having its rotor connected by a mechanical linkage to the elevator cab and turned by the movement of the cab, one winding of said Selsyn being connected to said signal source, means for producing an auxiliary A. C. signal having an amplitude which varies in accordance with the speed of the elevator cab, and means responsive to the difference between the amplitude of each signal

produced across the other winding of said Selsyn and the amplitude of said auxiliary signal for controlling the movement of the elevator cab.

21. An elevator control system comprising a signal source adapted to produce signals which increase by an increment for each floor level, a variable signal source adapted to produce a second signal variable with the height of the elevator car, means for selectively comparing said first signals with said variable signal and producing control signals proportional to the vector sum of said first and second signals, means responsive to said control signals for actuating the elevator car at a speed proportional thereto, and means responsive to the deceleration of the elevator cab for lessening the rate of decrease of said control voltage, thereby limiting the rate of deceleration.
